UNITED STATES PATENT OFFICE

LEWIS T. BARKSTROM, OF CHICAGO, ILLINOIS, ASSIGNOR TO J. P. SEEBURG PIANO COMPANY, OF CHICAGO, ILLINOIS, A CORPORATION OF ILLINOIS

TRACKER AND CLEANING DEVICE FOR MUSIC SHEETS FOR AUTOMATIC MUSICAL INSTRUMENTS

Application filed July 15, 1927. Serial No. 205,999.

This invention relates to an improvement in a tracker and cleaning device for music-sheets for automatic musical instruments.

The principal objects of the invention are 5 to provide a simple and economical construction which will improve the cooperative action of the tracker with the music-sheets as they are drawn thereacross to control the operation of the instrument and which will 10 guard against the entrance of dust, lint, or other particles of foreign matter from the music-sheets into the tracker-apertures and into the instrument air-passages connected therewith. 15 Other important objects are to provide a construction of the aforesaid character which may be applied to any standard type of sheet-controlled instrument; which is entirely automatic in operation and does not involve the 20 addition of, or connection with, movable control-elements; which provides for the screening and collection of the aforesaid dust, lint, or other particles of foreign matter in a conveniently accessible receptacle, itself of novel 25 and advantageous construction; and which will require a minimum amount of attention, the only attention necessary being that concerned with the occasional removal of the collected foreign matter from the aforesaid 30 receptacle.

These and other objects and advantages of the invention will more fully appear from the detailed description to follow.

In the drawings,

35 Figure 1 is a front elevational view of what is generally termed the upper structure of a conventional type of automatic musical instrument, illustrating the customary arrangement of the tracker-and-spool box, the sheet-propelling motor, and the player-action, and showing the preferred location and general arrangement of the construction embodying the present invention;

40 Fig. 2 is a vertical sectional view, upon an enlarged scale, taken upon the line 2-2 of Fig. 1, illustrating the construction and connection of the parts here directly involved;

45 Fig. 3 is a perspective view of the screening and collecting receptacle forming a part 50 of this invention, with the front cover of the

receptacle removed and the screening element partially withdrawn;

Fig. 4 is a perspective view of one end-portion of the tracker, constructed according to this invention; and

55 Fig. 5 is a sectional plan view of the tracker, taken upon the line 5-5 of Fig. 4.

Before proceeding with the detailed description of the present construction, it may be well to point out, in a general way, where-in this invention differs in purpose, as well as in application and form, from others which may at first appear to be similar.

60 The usual operation of an automatic musical instrument involves the passing of perforated paper music-sheets across the apertures of the tracker and it is well known that, during the playing operation of the instrument, each tracker-aperture constitutes the inlet end of a suction duct or channel and any dust or lint (and often punching scraps) which may be dislodged from the tracker-contacting surfaces of the music-sheets, and from the edges of the perforations therein, is usually sucked into the tracker-apertures and into the 65 instrument air-passages connected therewith. In short, the row of tracker-apertures undesirably constitutes a fairly efficient cleaning device for the music-sheets during each playing operation of the instrument. It is also 70 well known that, during the rewinding of the music-sheets, air-tension is cut off from the tracker-apertures and from the instrument air-passages connected therewith, and the 75 instrument during each playing operation not only adheres to the walls of the aforesaid apertures and passages, but lodges or pockets in the various angles and recesses thereof and accumulates in matted formations which may not be withdrawn by such 80 methods as are generally practiced. These 85 generally practiced methods involve the employment of various arrangements and devices for reversing the draft of air through the passages during the rewinding operation of the instrument and for pumping out the 90

95 instrument during the playing operation. These 100 methods are not only time consuming, but are also liable to damage the instrument.

tracker-apertures and instrument air-passages, but they have proven to be only partially effective in removing accumulated foreign matter. In most instances, such foreign matter continues to accumulate until it interferes with the operation of the instrument and eventually necessitates the removal of the usual valve-operating diaphragm-pneumatics in order to reach and remove the matted masses or wads of material accumulated therebeneath.

The only practicable way to prevent this accumulation of foreign matter and avoid the trouble produced thereby appears to be to guard against its entrance into the tracker-apertures and, in order to do this, the tracker-contacting surfaces of the music-sheets and the edges of the music-sheet-perforations must be cleaned of such foreign matter before it can be sucked into the tracker-apertures. Furthermore, the cleaning operation should be effective throughout the playing operation of the instrument, when the tracker-apertures are effective, and should remove the foreign matter from the music-sheets just before it is carried to the tracker-apertures, acting, in effect, to deflect all dislodgable material from the music-sheets from entering the said tracker-apertures and instrument air-passages and to effect this deflection at a point close to said tracker-apertures, so that there may be no opportunity for additional material to be rubbed loose from the music-sheets by friction thereof upon any considerable intervening surface of the tracker.

Accordingly, the present invention provides for cleaning all that portion of a music-sheet which is to pass over and between the tracker-apertures immediately before it reaches them, the cleaning operation being effective throughout the forward or playing movement of the sheet and so long as the tracker-apertures are provided with suction. In the present arrangement, this cleaning operation is designed to be fully as effective and powerful in removing the foreign matter from the sheet as are the tracker-apertures. These distinguishing features, together with the improvement herein provided in the co-operative action of the tracker with the music-sheets, will be better understood as the description proceeds.

Referring, first, to Figure 1 of the drawings, it will be seen that the tracker-and-spool box 1 houses the tracker 2, the music-roll 3, the music-sheet 4, and the take-up spool 5; that the music-sheet-propelling motor 6 is located at the right of box 1 and is connected, by the gearing 7, with the spindles of music-roll 3 and take-up spool 5; and that box 1 and motor 6 are each positioned above the player-action 8. Tracker 2 is provided with the usual row or range of apertures 9 for co-operation with the perforations in the music-sheet 4 to control the operation of the various

automatically controllable devices of the instrument, and motor 6 operates, according to the adjustment of gearing 7, to alternately advance and rewind the music-sheet. In the advancement of the music-sheet, it is unwound from music-roll 3, drawn across tracker 2, and wound upon take-up spool 5 and, coincident with the adjustment of gearing 7 to effect this advancement, player-action 8 is placed in pneumatic communication with the wind-supplying devices of the instrument (illustrated diagrammatically at 30) to effect the rarefaction of air therein and in the air-passages thereof which are connected with tracker-apertures 9, so that, when motor 6 is set in operation, the advancement of the music-sheet-perforations across the tracker-apertures will effect the opening and closing thereof and the consequent admission and cutting off of atmospheric air thereto to control the operation of the note-valves of the player-action in a manner to be described. In the rewinding of the music-sheet, it is unwound from take-up spool 5 and re-wound upon music-roll 3 and, coincident with the adjustment of gearing 7 to effect this rewinding, the player-action is cut off from pneumatic communication with the wind-supplying devices (as by means of the cut off valve shown diagrammatically at 31), so that, there being no rarefaction of air in the player-action or in the aforesaid air-passages thereof which are connected with the tracker-apertures, the return of the music-sheet-perforations across the tracker-apertures will be ineffective and the musical selection represented thereby will not be played backwardly. The arrangement and operation of the parts just mentioned are not novel, but it is important to note that the tracker-apertures 9 are effective as suction-ducts when the music-sheets are being advanced and not when they are being rewound.

Player-action 8 comprises the usual air-chambers, such as 10 (Fig. 2), series of note-valves, such as 11, and corresponding series of valve-actuating diaphragm-pneumatics, such as 12. Valves 11 are individually operated by their respective diaphragm-pneumatics 12 to control the pneumatic connection of corresponding power-pneumatics (not shown) alternately with the atmosphere and with the air-chamber 10, all in the usual or any desired manner. Each diaphragm-pneumatic 12 is cemented, or otherwise secured, over an individual cell or recess 13 formed in the bottom wall of air-chamber 10, and each cell 13 communicates, through a duct and tracked-tube 14, with one of the tracker-apertures 9 and, through a pin-hole vent 15, with air-chamber 10.

The playing operation of the instrument includes the withdrawal of air from air-chamber 10 and the advancement of music-sheet 4 across tracker 2. The withdrawal of

air from air-chamber 10 reduces the air-pressure therein, and also reduces the air-pressure in each tracker-tube 14 through the communicating vents 15 and, so long as the connected corresponding tracker-apertures 9 are covered by imperforate portions of music-sheet 4, both sides of diaphragm-pneumatics 12 will be subjected to the reduced air-pressure and they will remain inactive. When a music-sheet-perforation registers with a tracker-aperture 9, a greater amount of atmospheric air enters the connected tracker-tube 14 than can be withdrawn therefrom through the corresponding vent 15, and the respective diaphragm-pneumatic 12 is sucked upwardly by the reduced air-pressure in air-chamber 10, acting to lift the corresponding note-valve 11 and effect the sounding of a note through the operation of the connected power-pneumatic, all in the aforesaid usual or any desired manner.

Now it is to be observed that, as the aforesaid upward movement of the diaphragm-pneumatics is occasioned by the admission of atmospheric air through the respective tracker-apertures, some of the dust, lint, or other particles of foreign matter which enters said tracker-apertures will be drawn past the corresponding vents into the cells beneath said diaphragm-pneumatics each time the upward movement thereof is effected. Although some of this foreign matter may be withdrawn from the cells through the vents into the air-chamber, when the respective tracker-apertures are again covered by the imperforate portion of the music-sheet, it is known that a certain amount remains lodged or trapped in the cells and often accumulates therein until it forms a dust-mat or felt-like cushion which interferes with the complete return of the diaphragm-pneumatics and prevents the respective note-valves from properly closing, thereby causing air-leakage. When a number of the note-valves are thus held from closing, the total leakage becomes noticeably apparent in the operation of the instrument, and this leakage is exceedingly difficult to locate and even more difficult to remedy. The only known method of removing these accumulated matted formations requires the removal of the diaphragm-pneumatics, as hereinbefore mentioned, and their removal usually involves their destruction and the necessary substitution of a new set.

According to this invention, tracker 2 is provided with a continuous slot 16 which extends closely parallel to and along the entire row or range of tracker-apertures 9. Slot 16 opens directly, and approximately throughout its length, into a chamber 17, here shown as formed by a tube 18 secured to the rear surface of the tracker-shell. Preferably, the opposite end-parts of tube 18 are bent to facilitate the connection of a pair of conduits 19 and 20, as illustrated in Fig. 5. Conduits

19 and 20 extend to a dust screening and collecting receptacle 21, and serve to connect chamber 17 therewith. As illustrated in Fig. 1, receptacle 21 is located upon the top of the player-action 8, below motor 6, where it may be conveniently reached, and is in the form of a box having a removable front cover 22 and a removable, horizontally arranged partition 23 (Fig. 3). Partition 23 divides the receptacle into upper and lower chambers 24 and 25, respectively (Fig. 2), is slidably mounted in grooves 26-26 (Fig. 3), and is provided with a screened aperture 27, through which said chambers communicate. Preferably, aperture 27 is of ample size to provide for the employment of a fine meshed screen 28 of considerable area, the advantage of this being too evident to require explanation. Conduits 19 and 20 open into the rear, and near the opposite ends, of lower chamber 25, and upper chamber 24 is connected with the wind-supplying devices of the instrument. As shown in Fig. 2, this connection is preferably made, through a conduit 29, with air-chamber 10 of player-action 8, so that the same valve 31 (Fig. 1) which controls the connection of the player-action with the wind-supplying devices 30 will also control the effectiveness of the cleaning device. With this arrangement, no additional valves or control-elements are required; no attachments to movable parts are necessary; the same degree of reduced air-pressure is served to the receptacle 21 and slot 16 as is served to the player-action 8 and tracker-apertures 9; and the cleaning device will be alternately rendered effective and ineffective automatically and simultaneously with the similar conditioning of the player-action.

Now, when the instrument is to be played, the usual adjustments are made (such as the opening of valve 31) to connect player-action 8 with the wind-supplying devices, and to set gearing 7 and operate motor 6 to effect the advancement of music-sheet 4 across tracker 2. Simultaneously with the withdrawal of air from the player-action to effect the operation of note-valves 11 under the control of the music-sheet-perforations, as hereinbefore described, air will also be withdrawn, through conduit 29, from upper chamber 24 of receptacle 21, and the suction thus created therein will extend, through screened aperture 27, to chamber 25 and thence, through conduits 19 and 20, to tube-chamber 17 and slot 16. The suction thus acting through slot 16 upon the tracker-contacting surface of the music-sheet, and upon the edges of all of the perforations therein, is fully as effective and powerful in removing the foreign matter from the sheet as is its action through tracker-apertures 9.

The arrangement of chamber 17 as a component part of tracker 2 provides for the construction and marketing of the tracker as

a complete unit, properly trued and surfaced, ready for installation in any standard type of sheet-controlled instrument, thus avoiding the chances of misadjustment which often occurs where separate elements or attachments are positioned to contact with the music-sheets and where a slight misadjustment seriously interferes with the proper "lay" of the sheets upon the surface of the tracker. It also provides for the proper location of the continuous slot 16 close to the row or range of tracker-apertures 9 which, in addition to the described advantage obtained by cleaning the sheets just before they pass over said apertures, also operates to draw them snugly down upon the surface of the tracker, close to said apertures, thereby presenting a smooth, clean, air-tight contact between the sheets and the tracker and avoiding the necessity of employing the usual sheet-tensioning friction-brakes and sheet-pressing devices. The provision of a continuous slot, such as here shown at 16, insures the cleaning of all that portion of the music-sheets which passes over and between the tracker-apertures 9 and avoids the fouling or clogging of the inlet with particles of foreign matter, either of which would not be possible if small separate openings and passages were employed. The connection of chamber 17 with the lower chamber 25 of receptacle 21 avoids clogging of the meshes of the screening element, since the foreign matter drawn into said lower chamber is arrested by the screen 28 and any appreciable collection of said foreign matter upon the lower side of said screen falls of its own weight to the bottom of the chamber. When it is desired to remove the collected foreign matter from the receptacle 21, the front cover 22 thereof is removed and the dust taken out with or upon a sheet of paper. The partition 23 may also be withdrawn from the receptacle, in the manner indicated in Fig. 4, and a light tap thereof or thereupon will serve to dislodge the dust collected upon the screen 28.

The connection of the cleaning device with the air-passages of the player-action avoids the necessity of additional valves or movable control-elements and provides a very simple arrangement for rendering the device effective during the playing operation and ineffective during the rewinding operation of the instrument. The effectiveness of the device in cleaning, smoothing, and steadyng the music-sheets as they are advanced across the tracker to control the playing of the instrument is thus brought about each time the tracker-apertures are rendered effective, and the device is likewise rendered ineffective simultaneously with the tracker-apertures during the rewinding operation, so that its action upon the music-sheets will not inter-

fer with the free and rapid rewinding thereof.

The construction and operation of the device having been fully described, what is claimed is—

1. In an automatic musical instrument, the combination of a tracker having a row of apertures and a continuous slot extending parallel therewith, a screening device connected with said slot and means operating 75 to alternately apply and discontinue the application of suction to said row of apertures and to said screening device and said slot simultaneously.
2. In an automatic musical instrument, 80 the combination of a tracker having a row of apertures and a continuous slot extending parallel therewith, a pneumatic action connected with said row of apertures, a screening device connected with said slot, and means operating to alternately apply and discontinue the application of suction to 85 said action and said device simultaneously.
3. In an automatic musical instrument, 90 the combination of a tracker having a row of apertures and a continuous slot extending parallel therewith, a pneumatic action connected with said row of apertures, and a screening device connected with said slot and with said action.
4. A music sheet cleaning device for automatic musical instruments comprising a tracker having a row of apertures and a continuous slot extending parallel therewith, a suction-producing device, and a screening 100 device having an upper chamber and a lower chamber communicating with each other through a screened partition aperture, a communication extending from said lower chamber to said slot, and a communication 105 extending from said upper chamber to said suction-producing device.
5. A music sheet cleaning device for automatic musical instruments comprising a tracker having a row of apertures and a continuous slot extending parallel therewith, a tube extending lengthwise of said tracker and secured thereto, said slot opening throughout its length into said tube, a screening 110 device having an upper chamber and a lower chamber communicating with each other through a screened partition aperture, a suction-producing device, a pair of conduits extending one from each end of said tube and connected with said lower chamber, 120 and a conduit extending from said upper chamber and communicating with said suction-producing device.
6. In an automatic musical instrument, 125 the combination of a tracker having a row of apertures and a continuous slot extending parallel therewith, a music-sheet roll positioned parallel with said tracker, means operating to draw the music-sheet from said roll and across said tracker in one direction 130

to control the playing of said instrument and to propel said music-sheet in the reverse direction across said tracker and rewind it upon said roll, and suction-producing means connected with said apertures and with said slot and operating to produce suction therein while said means is operating to draw said music-sheet across said tracker in said one direction; the position of 5 said slot being between said row of apertures and said roll.

7. In an automatic musical instrument, the combination of a tracker having a row of apertures and a continuous slot extending parallel therewith, a music-sheet roll positioned parallel with said tracker, means operating to draw the music-sheet from said roll and across said tracker in one direction to control the playing of said instrument 10 and to propel said music-sheet in the reverse direction across said tracker and rewind it upon said roll, suction-producing means, pneumatic connections extending from said apertures and slot to said suction-producing 15 means, and a cut-off operating to permit the application of suction to said apertures and slot while said music-sheet is being drawn across said tracker in said one direction and to prevent the application of 20 suction to said apertures and slot while said music-sheet is being propelled in said reverse direction across said tracker; the position of 25 said slot being between said row of apertures and said roll.

30 35 In witness whereof, I have hereunto subscribed my name this 12th day of July, A. D. 1927.
